Primary Examiner — Catherine S Posthauer*Assistant Examiner* — Joan E. Diehl(74) *Attorney, Agent, or Firm* — Daniel M. Cohn; Howard M. Cohn(57) **CLAIM**

The ornamental design for a silicone dips container, as shown and described.

DESCRIPTION

FIG. 1 is a perspective view of a silicone dips container showing my new design in a closed configuration; FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the silicone dips container, shown in an open configuration.

The dash-dash broken lines in the drawings depict portions of the silicone dips container that form no part of the claimed design.
